REFINING OF MINERAL OILS

Malcolm H. Tuttle, New Rochelle, N. Y., assignor
to Max B. Miller & Co., Inc., New York, N. Y., a
corporation of Delaware

Application January 31, 1934, Serial No. 709,098

3 Claims. (Cl. 196—13)

This invention relates to the refining of mineral oils by means of solvents, and more particularly to improvements in processes of the type in which a mineral oil is separated into a paraffinic type oil (especially useful for lubricating internal combustion engines and the like), and into a naphthenic type oil, by means of a solvent for the former and a solvent or solvents for the latter. Examples of such processes are disclosed in the present inventor's copending application Ser. No. 623,483, filed July 20, 1932 and in his Patent No. 1,912,349, issued May 30, 1933. The present application is in part a division of said application Serial No. 623,483.

15 A feature of the present invention resides in providing for the improvement of the properties of a paraffinic type oil in a simple and efficient manner.

More specifically, a feature of the invention is the provision of a process of this character in which naphthenic solvent is employed to cause an efficient separation of desired quality paraffinic oil from a fraction of lubricating oil already highly paraffinic in character, and to enable a ready 25 recovery of a large portion of the naphthenic solvent for reuse without the need for evaporating much of this solvent from the oil.

Another feature of the present process is the production of a paraffinic type oil having a high 30 viscosity index (a relatively small reduction in viscosity for a given rise of temperature) and an improved color.

Other objects, features, and advantages of the invention will become apparent as the following 35 detailed description of an example of the present process proceeds, reference being had to the accompanying drawing wherein:

The figure is a diagrammatic flow-sheet of a process in accordance with the invention.

40 With reference to the flow-sheet, a charge oil to be treated, which may be an overhead distillate, a residual oil, or other mineral oil from which a paraffinic type oil is to be separated, may be introduced into extraction apparatus of convenient 45 construction, and may be treated with counter-flowing paraffinic and naphthenic solvents adapted to form solutions which are miscible to but a limited extent so that they tend to separate into layers. For instance, a paraffinic solvent, such 50 as a liquefied normally gaseous hydrocarbon (propane or the like) or a liquid hydrocarbon (petroleum ether or the like), may be introduced at the bottom of an extraction tower and a suitable naphthenic solvent, such as commercial 55 cresylic acid, or other known naphthenic solvent,

or mixtures of one or more of them with pyridine, furfural, analine, or liquid sulphur dioxide, or the like, may be introduced at the top of the tower, so that the solvents counterflow, or in other words so that the paraffinic oil fraction or raffinate is washed with naphthenic solvent and the naphthenic oil fraction or extract, removed from the presence of the charge oil, is washed with paraffinic solvent.

The operations may be conducted continuously 10 or by batch treatment, and the extraction may be carried out in a series of separate chambers, or repeated, if desired. The amounts of solvents may vary depending upon the nature of oil to be treated, but in general may advantageously be 15 sufficient to readily dissolve their respective oil fractions. The temperature of the mixture is advantageously maintained below the critical temperature at which the solvents become miscible. This temperature varies for different solvents but may be readily determined for given solvents. Where normally gaseous solvents are employed, the mixture in the extraction apparatus should be under sufficient pressure to maintain the solvents liquid, and the apparatus is then 20 25 preferably maintained full of liquid. Any convenient pumps and control devices may be employed for this purpose.

The paraffinic layer or raffinate leaving the top of the primary extraction apparatus will contain 30 paraffinic type oil, paraffinic solvent and some entrained or entrapped naphthenic solvent, and the paraffinic solvent may next advantageously be removed and returned as indicated for reuse. The removal of the paraffinic solvent may be accomplished by means of an evaporator where 35 the boiling point of this solvent is lower than that of the naphthenic solvent, as is preferably the case. However, it may be removed in other ways if more convenient.

The paraffinic oil and naphthenic solvent passing from the evaporator are next preferably but not necessarily mixed with additional naphthenic solvent and fed to separator where the resulting mixture is allowed to form layers. Upon reducing the ratio of paraffinic solvent to naphthenic solvent, a rather remarkable result is achieved, for the upper layer will be found to contain by far the major portion of the paraffinic oil and markedly less naphthenic solvent than the mixture entering the separator contained, and the lower layer will contain only a few percent of oil and markedly more naphthenic solvent than was added to the mixture entering this separator.

The upper layer in the separator may then be 55

withdrawn and the naphthenic solvent remaining therein may then be removed as by evaporation. The oil thus produced will be found to have an extremely light color and a high viscosity index, 5 being considerably improved in these respects over the oil resulting from merely removing the solvents from the paraffinic layer leaving the primary extraction apparatus.

The naphthenic solvent, containing small 10 amounts of oil and forming the lower layer in the separator, is preferably withdrawn from the bottom of the separator and pumped into the primary extraction apparatus as shown, being supplemented, if desired, by additional naphthenic 15 solvent pumped from a suitable storage reservoir. The solvent in this reservoir may be supplied principally by naphthenic solvent recovered from the naphthenic oil fraction or extract leaving the primary extraction apparatus and recovered from 20 the paraffinic oil fraction leaving the separator, additional solvent to compensate for losses being added to the storage reservoir as required. Similarly, paraffinic solvent may be recovered from 25 the naphthenic oil fraction leaving the extraction apparatus. Suitable valves may be provided for controlling the proportions of naphthenic solvent fed to the extraction tower and to the mixture entering the separator, or for by-passing the solvent around the latter, if desired, under certain 30 conditions.

By way of a specific example, a distillate from a San Joaquin crude having a viscosity index of -51 was treated in accordance with the present process with solvents totalling 300% by weight 35 of propane and 800% by weight of cresylic acid, based upon the weight of the oil treated, and paraffinic oil fraction, amounting to 26% of the oil treated, was produced having a viscosity index of 100 and an N. P. A. standard color of 1 to 1½. 40 Moreover, it appears that the viscosity index is increased from about 85 to 100 and that the N. P. A. color shows an improvement of 1 to 1½ points, by virtue of the separation step in which naphthenic solvent is added to the paraffinic fraction 45 and the mixture is permitted to form layers. In addition the yield secured was high, while at the same time the need for evaporating large amounts of solvent was avoided. More specifically, whereas the paraffinic layer leaving the primary extraction apparatus contained about 50 50 parts of oil to 50 parts of cresylic acid, the upper layer withdrawn from the separator contained about 85 parts of oil and only 15 parts of cresylic acid. Advantages are secured, however, even 55 though this upper layer is composed of only 75 parts of oil and 25 parts of cresylic acid, or even less oil and more acid. On the other hand the lower layer from the separator contained only 3 to 5% of oil. Similar, but possibly somewhat less 60 marked advantages may be achieved with residual oils.

If desired the oil in the separator may be cooled or heated somewhat to promote the separation into layers, though this is not deemed to be essential. It will be appreciated that the evaporation of propane or other liquefied normally gaseous hydrocarbon in the evaporator has the effect of lowering the temperature of the mixture, and

also of reducing the ratio of paraffinic solvent to naphthenic solvent.

Through the present development there is provided a simple and efficient process for producing a high grade paraffinic type oil without the need 5 for distilling or evaporating large amounts of solvents. Moreover, the recovered naphthenic solvent is well adapted for direct reuse in the process. The paraffinic type oil produced is a good yield of oil having a high viscosity index and an 10 excellent color, in some cases practically water white. Moreover, the apparatus required is simple and efficient, both in construction and in operation.

While the invention has been described in connection with certain features set forth in my patent and application to which reference has been made, and while it has especial advantages when employed in connection with such a process, it may enjoy a more general application and accordingly is not to be limited in its broader aspects save by the appended claims.

The terms and expressions which have been employed are used as terms of description and not of limitation, and there is no intention, in 25 the use of such terms and expressions, of excluding any equivalents of the features shown and described, or portions thereof, but it is recognized that various modifications are possible within the scope of the invention claimed.

What is claimed is:

1. In the art of refining a mineral oil by means of liquefied propane and a separable naphthenic solvent, the steps comprising counterflowing said propane and solvent in the presence of the oil to be defined, separating from the resulting mixture a raffinate fraction containing oil, propane and solvent, evaporating at least a portion of the propane from said withdrawn raffinate fraction to cause the same to separate into layers, separating the layers thus formed and returning the bottom layer to the first-named step.

2. In the art of refining a mineral oil by means of separable paraffinic and naphthenic solvents, the steps comprising commingling said oil with both of said solvents, separating from the resulting mixture a raffinate fraction containing oil and portions of both of said solvents, reducing the ratio of paraffinic solvent to naphthenic solvent by removing at least a portion of the paraffinic solvent and by adding additional naphthenic solvent to cause the raffinate fraction to separate into layers, separating the layers, and employing the lower layer thus produced in the first step recited.

3. In the art of refining a mineral oil by means of separable paraffinic and naphthenic solvents, the steps comprising commingling said oil with said solvents, separating from the resulting mixture a homogeneous raffinate fraction containing oil, paraffinic solvent and naphthenic solvent, removing at least a portion of said paraffinic solvent from the raffinate, to cause the raffinate layer to separate into an upper layer and a lower layer containing only a few per cent. of oil and most of the naphthenic solvent of the raffinate, withdrawing said lower layer, and employing the same in the first step recited.
